ELECTRIC IRON

Austin E. Cox, Wadsworth, Ohio, assignor to Dominion
Electric Corporation, a corporation of Ohio

Filed Aug. 21, 1963, Ser. No. 76,304

Term of patent 14 years

(Cl. D49—6)

FIG. 1

FIG. 2

FIG. 3

FIG. 4

FIG. 5

FIG. 6

FIGURE 1 is a top plan view of an electric iron embodying my design;

FIGURE 2 is a side elevational view thereof;

FIGURE 3 is a rear elevational view thereof;

FIGURE 4 is a front elevational view thereof;

FIGURE 5 is a front elevational view of a modified form of the iron shown in FIGURES 1 to 4; and

FIGURE 6 is a side elevational view thereof.

The cord is shown broken away in FIGURES 1, 2 and 6, and omitted in FIGURE 3 for convenience of illustration.

I claim:

The ornamental design for an electric iron, substantially as shown.
